UNITED STATES PATENT OFFICE.

PAUL ROUSSEY, OF BROOKLYN, NEW YORK.

PERMUTATION ALARM AND CIRCUIT-CLOSER FOR SPARKING PLUGS.

1,161,890.

Specification of Letters Patent.

Patented Nov. 30, 1915.

Application filed July 21, 1914. Serial No. 852,275.

To all whom it may concern:

Be it known that I, PAUL ROUSSEY, a citizen of France, residing at Brooklyn, in the county of Kings and State of New York, 5 have invented new and useful Improvements in Permutation Alarms and Circuit-Closers for Sparking Plugs, of which the following is a specification.

This invention relates to permutation 10 alarms and circuit closers for sparking plugs and consists in the novel features hereinafter described and claimed.

An object of the invention is to provide a device of the character indicated especially 15 adapted to be used upon automobiles the parts of the device being so arranged that in the event that a person unfamiliar with the combination of the movable parts attempts to operate the device an alarm is 20 sounded and consequently attention is attracted to the machine. On the other hand the parts of the device are so assembled and arranged that one who is familiar with the proper combination may easily and quickly 25 manipulate the movable parts to establish or complete the circuit from the magneto of the machine to the sparking plugs of the engine cylinders.

A further object of the invention is to 30 provide in a device of the character indicated means for easily and quickly changing the combination of the parts in order that the owner or authorized user of the machine may be assured that the machine will not be 35 used during his absence without danger of an unauthorized person attempting to use the same being detected.

With these and other objects in view the device consists in the novel features and 40 structural arrangement of parts as will be hereinafter described and more particularly pointed out in the appended claims.

In the accompanying drawing: Figure 1 45 is a side elevation of the forward portion of an automobile showing the alarm and circuit closer for sparking plugs in position thereof. Fig. 2 is a transverse sectional view of the instrument forming the principal part of the device. Fig. 3 is a 50 transverse sectional view of the said instrument cut on the line 3—3 of Fig. 2. Fig. 4 is a perspective view of operating parts of the instrument. Fig. 5 is a plan view of an arm supporting disk 10 in the instrument. 55 Fig. 6 is a perspective view of an arm used in the instrument. Fig. 7 is a diagrammatic

view showing the parts of the instrument closed for completing the circuit to the sparkers of the engine. Fig. 8 is a similar view showing the circuit which leads to the 60 alarm bell closed.

The instrument of the device comprises a base 1 adapted to be mounted upon a support 2 attached to the dash 3 of an automobile as most clearly illustrated in Fig. 1 of 65 the drawing. A casing 4 is mounted upon the base 1 and is detachably secured thereto by means of securing devices 5 of any desired form or pattern. A cover 6 is hingedly connected with the casing 4 and is provided 70 at one side with an outstanding lug 7 adapted to be engaged by a spring catch 8 mounted upon the casing 4 whereby the said cover 6 is held in a closed position with relation to the casing.

An annular member 9 fits snugly within the casing 4 and is connected at its lower edge with the base 1. The casing 4 is provided at its upper end with a top wall 10 which extends over the upper edge of the annular member 9 and which is provided at equal distances from its center and in the vicinity of its periphery with a number of circularly arranged openings 11. A ring 12 is fixed in the upper portion of the annular member 9 85 and is provided with a series of sockets 13 which correspond in number with the openings 11 and which are in longitudinal alignment with the same. The ring 12 is of insulating material. Stems 14 are mounted 90 for movement transversely through the ring 12 and traverse the length of the sockets 13. The said stems 14 are provided at their upper ends with key heads 15. Stops 16 are mounted upon the intermediate portions of 95 the stems 14 and are located in the sockets 13. Coil springs 17 are interposed between the bottom of the sockets 13 and the under sides of the stops 16 and are under tension with a tendency to normally hold the stems 100 14 in elevated positions and the upper surfaces of the stops 16 against the lower surfaces of nuts 18 which are screw threaded in the upper ends of the sockets 13 and through which the stems 14 slidably pass. The stems 105 14 are provided at their lower ends with laterally disposed branches 19 and inwardly disposed branches 20 most clearly shown in Figs. 2 and 4 of the drawing.

A stud 21 passes through the center of the 110 base 1 and is surrounded by a boss 22 provided upon the said base. A gasket 23 is

screw threaded upon the boss 22 and is spaced from the upper surface of the base 1. A disk 24 is turnably mounted upon the base 1 and is held down in position upon the same by means of the gasket 23. The disk 24 is provided at its peripheral portion with a number of recesses 25 having undercut shoulders 26. An electric wire 27 is connected with the disk 24 and passes through the gasket 23 and base 1 and is connected with a bell 28 preferably mounted under the seat of the automobile as indicated in Fig. 1. The said bell in turn is connected with batteries 29 and a wire 30 connects the said batteries with a ring 31 mounted upon the ring 12. The wire 30 also passes through the base 1 and the gasket 23 as best indicated in Fig. 3 of the drawing. A series of contacts 32 are mounted upon the ring 31 and have engagement with the sides of the stems 14, hereinbefore described. The turning movement of the disk 24 is limited by means of a pin 33 which passes through a slot 34 provided in the said disk and which enters the base 1. The said pin and slot device is best illustrated in Fig. 3 of the drawing. A pulling spring 35 is connected at one end with the gasket 23 and at its other end with the disk 24 and is under tension and serves to hold one end of the slot 34 in contact with the side of the pin 33 as shown in Fig. 3 of the drawing.

Arms 36 are provided at their inner ends with pins 37 which enter sockets provided in the intermediate portion of the base 1 as best indicated in Fig. 2 of the drawing. The said sockets in the base 1 are arranged in circular form as indicated at 37' in Fig. 5 of the drawing. A washer or disk 38 is mounted upon the inner ends of the arms 36 and holds the pins 37 in the sockets of the base 1.

Fig. 5 is a plan view of the washer or disk 38. The arms 36 are two in number and one of them is connected by means of a wire 39 with a magneto 40 best shown in Fig. 7 of the drawing. The wire 39 passes through the gasket 23 and the base 1 at the same openings therein through which the wires 27 and 30 pass. Resilient arms 41 are supported upon the upper portions of the washer 38 and are provided at their inner ends with pins 42 which enter the sockets 37' provided in the said washer. The arms 41 are also two in number and each arm is provided with a depending portion 43 which is adapted to encounter the arms 36 located below the same when the arm 41 is depressed as best indicated at the right hand part of Fig. 2.

Fig. 6 is a perspective view of the arm 41. One of the arms 41 is connected by means of a wire 44 with that arm 36 other than the said arm 36 which is connected

with the wire 39 as best shown in Fig. 7 of the drawing. The other arm 41 is connected by means of a wire 45 with the magneto 40 hereinbefore described. A washer 46 is located upon the upper portion of the stud 21 and holds the arm 41 in proper position against the washer 38. A wing nut 47 is screw threaded upon the upper end of the stud 21 and holds the part 46, arms 41 and 36 and 38 in proper relation with respect to each other. The arms 41 may be disposed in radial alinement with relation to each other as indicated in heavy lines in Fig. 3 of the drawing or the said arms may be disposed at angles with relation to each other as indicated by the dotted lines in said figure. By so mounting the arms means is provided for changing their positions whereby the combination for operating the device may be changed at will. To effect the adjustment of the arms 41 and 36 the securing device 5 is removed from the base 1 and the casing 4 together with the annular member 9 is removed from the base 1 and consequently the ring 12 and the parts supported thereon are removed from over the arms 41 and 36 then by loosening the wing nut or removing the said wing nut from the stud 21 the washer 46 may be removed and the arms 41 may be positioned at desired points upon the washer 38 then by removing the washer 38 the arms 36 may be placed at corresponding points upon the gasket with relation to the arms 41. After this has been done the parts are reassembled and the desired combination of parts is had. The magneto 40 of the engine is connected with the sparking plug of the engine by means of a wire 48 as best illustrated in Fig. 7 of the drawing. The arms 41 are provided at their outer ends with upstanding stops 49 which are located in the paths of movement of two of the inner branches 20 of two of the stems 14 as best indicated in Fig. 2 of the drawings. The arms 41 are further provided at their outer ends with pieces of insulation 50 adapted to engage catch members (hereinafter to be described) when the said arms 41 are depressed as shown at the right in Fig. 2 of the drawing.

Two types of standards are provided for engaging under the shoulders 26 of the recesses 25 provided upon the disk 24. One type of standard is shown at 51 in Fig. 4 and the other type at 52 in the said figure. The standards 51 are provided with flexible side portions 53 adapted to enter the recesses 25 and provided at their lower ends with outstanding flanges 54 adapted to engage under the shoulders 26. The said standards 51 are provided at their upper ends with inclined surfaces 55 which are located in the paths of movement of the branches 19 of the stems 14 located above the said standards 51. By pressing the side portions 53

of the standards 51 toward each other the said standards may be readily detached from the recesses 25 and positioned in any of the recesses desired.

5 The standards 52 are also provided with flexible side portions indicated at 56 and the said portions are adapted to enter some of the recesses 25. The side portions 56 of the standards 52 are provided at their lower 10 ends with flanges 57 adapted to engage under the shoulders 26 of the recesses 25 in which the said standards 52 are positioned as best shown in Fig. 2 of the drawing. The standards 52 are provided at their inner side 15 portions 56 with catches 58 the upper surfaces of which are beveled or inclined as best shown in Figs. 2 and 4 of the drawing. These catches 58 are located in the paths of movement of the insulated projections 50 upon the ends of the arms 41. The standards 52 at their upper ends are devoid of 20 inclined surfaces such as those described as 55 in connection with the standards 51 and the branches 19 of the stems 14 which are located above the standards 52 are unob- 25 structed in their downward movement along the edges of the said standards 52.

The operation of the device is as follows. When the device is used by one who is familiar 30 with the combination, that is to say the disposition of the arms 41 with relation to each other and with relation to the key heads 15 the cover 6 is swung back and the keys 15 of the proper combination are depressed or pushed in an inward direction. As the stems 14 which carry the said key heads move longitudinally the branches 20 thereof come in contact with the stops 49 upon the arms 41 and the said arms are depressed as indicated in the view in Fig. 7. At the same time the insulated extensions 50 of the said arms engage under the catches 58 and the depending portions 43 are held in contact with the arms 36. As the extensions 45 move along the catches 58 the inner sides of the standards 51 flex in an outward direction and consequently the said extensions may pass along the catches but as soon as the extensions pass below the catches the 50 sides of the standards 51 flex inwardly and the parts are held temporarily in the positions indicated. Therefore it will be seen by referring to Fig. 7 of the drawing that an electric connection is made through the wire 39 with the magneto 40 one of the arms 36 and along the depending portion 43 to the arm 41 above thence along the wire 44 to the other arm 36 then along the other depending portion 43 to the other arm 41 55 thence along the wire 45 back to the magneto and the said current passes along the wire 48 to the sparking plug of the engine. The parts are held in the positions just above described as long as the engine runs. 60 When the automobile or engine stops and it

is desired to lock the parts against the use of an unauthorized person the operator swings the cover 6 back and depresses any one of the stems 14 located above one of the standards 51. In doing this the branch 19 of the said stem passes along the inclined surface 55 of the standard 51 and the disk 24 is turned or moved against the tension of the spring 35 for a distance approximately equal to the length of the slot 34. 75 This carries the ends of the insulated extension 50 of the arm 51 beyond the sides of the catches 58 and inasmuch as the arms 41 are flexible they will swing or fly in an upward direction and assume their normal positions. As soon as the operator releases his pressure from the said stem 14 the tension of the spring 35 comes into play and the disk 24 is drawn back to its normal position. 80

Now let it be presumed that an attempt is 85 made by one who is not familiar with the combination or an unauthorized person. The said person depresses one of the stems 14 which is located above one of the standards 51 for the reason that he does not know 90 the proper stem to depress. As the said stem 14 is depressed the end 19 thereof encounters the inclined surface 55 of the standard 51 below and an electric circuit is made from the batteries 29 to the bell 28 in the 95 following manner and as is best illustrated in Fig. 8 of the drawing. The current passes from the batteries 29 along the wire 30 to the ring 31 thence through the contacts 32 to the stem 14 then along the said stem and branch 19 to the standard 51 thence to the disk 24 and thence along the wire 27 to the bell 28 sounding the same and then back to the batteries 29. Consequently 100 an unauthorized or any person who is unfamiliar with the combination will sound the alarm in an attempt to establish the electric circuit to the sparking plug. This alarm will warn the owner of the automobile and he may promptly take measures to protect 110 purloining of his property. 105

Having described the invention what is claimed is:—

1. In a device of the character described, a disk mounted for turning movement, 115 means for returning and holding the disk at a normal position, standards mounted upon the disk, normally spaced electric contacts located adjacent the disk, an electric circuit connected with the said contacts, key operated stems adapted to engage the contacts to close the circuit, means carried by some of the standards for holding the contacts closed, and other key operated stems having portions engageable with the standards to 120 turn the disk and thereby release the contacts from the holding means and open the circuit. 125

2. In a device of the character described a disk mounted for turning movement, means 130

for holding the disk at a normal position, standards adjustably mounted upon the disk, some of the standards being provided with catches and others with surfaces inclined with relation to the disk, contact arms located adjacent the disk, stems movably mounted adjacent the disk and having branches adapted to engage the contact arms to move the same below the catches and to establish electric connection between the said arms, other stems having branches adapted to engage with the inclined surfaces of the other standards.

3. In a device of the character described a disk mounted for turning movement, means for holding the disk at a normal position, recesses formed at the edge portion of the disk, standards having flexible sides and provided with flanges adapted to enter the recesses and engage under the same, some of the standards being provided with catches and other of the standards having surfaces inclined with relation to the disk, contact arms mounted adjacent the disk and adapted to be brought into engagement with each other, some of the said arms having extensions adapted to engage under the catches when the said arms are depressed, stems having branches, the branches of some of the stems adapted to depress the arms having the extensions and the branches of the other stems adapted to encounter the inclined sur-

faces of the standards provided with the same whereby the disk is turned against the tendency of its retaining means.

35

4. In a device of the character described a base, a disk movably mounted on the disk, means for holding the disk at a normal position upon the base, contact arms adjustably mounted upon the base, other contact arms adjustably mounted above the base and adapted when depressed to establish electric connection with the first mentioned contact arms, standards adjustably mounted upon the disk some of the standards having catches and other of the standards having inclined surfaces, movable keys having branches some of the keys adapted to depress the last mentioned arms whereby the said last mentioned arms are held in depressed condition by the catches and in electric contact with the first mentioned arms, other of the said stems having branches adapted to encounter the inclined surfaces of the standards provided with the same whereby the disk is moved against the tendency of its retaining means.
